UNITED STATES PATENT OFFICE.

CHARLES SUTTER, OF SURESNES, FRANCE, ASSIGNOR TO SOCIETE ANONYME DES ANCIENS ETABLISSEMENTS HOTCHKISS ET COMPAGNIE, OF ST. DENIS, SEINE, FRANCE.

FIRING REGULATOR FOR AUTOMATIC FIREARMS.

Application filed February 20, 1925. Serial No. 10,641.

To all whom it may concern:

Be it known that I, CHARLES SUTTER, a citizen of the French Republic, and residing at 42 Rue Emile Zola, Suresnes, Seine, France, have invented new and useful Improvements in Firing Regulators for Automatic Firearms, of which the following is a specification.

The present invention relates to a firing regulator for automatic fire-arms, that is to say, to a device which controls the movement in one direction of a member to which a reciprocating movement is imparted and which forms a part of the mechanism of the fire-arm, for the purpose of obtaining a predetermined rate of fire.

The regulating mechanism described below is of the kind in which the reciprocating member, after having effected its rearward movement, is stopped by a mechanism, the duty of which is to defer the movement of the said member forwardly, that is to say, to retain it in its rearmost position during a predetermined time and then to release it so as to enable it to return to its foremost position. In fire regulating mechanisms of this kind which have already been constructed, the mechanism in question stores up energy when the reciprocating member finishes its stroke towards the rear, and utilizes this energy, while at the same time deferring the movement of the said member forwardly, after which this mechanism releases the part in question. The regulating effect was generally obtained by means of a device utilizing dashpots, antagonistic springs, inertia systems, anchor escapements or the like.

According to the present invention, the fire regulating mechanism comprises, as regulating means, a fly-wheel which is rotated by the reciprocating member against the action of a spring which brings back the fly-wheel to its starting position.

The invention also comprises the following characteristics:

The reciprocating member, at the end of its rearward stroke, engages an intermediate sear, which is raised during the whole time that the fly-wheel rotates, but is free to sink as soon as this fly-wheel returns to its original position.

The fly-wheel is actuated by a pivoted lever which is engaged by the reciprocating member when this latter moves backwards. 55

The pivoted lever is mounted upon a shaft, the position of which can be modified so as to vary the relative positions of the said lever and of the reciprocating member, for the purpose of varying the extent 60 of the motion transmitted to the fly-wheel and, ultimately, to render such motion nil, the intermediate positions of the lever corresponding to different rates of fire.

In order to permit of single shot fire, the ordinary sear carries a pivoted catch which, when the trigger is drawn rearwardly, can engage in a notch of the fly-wheel and can retain this latter in a position in which, after having been actuated by the reciprocating member, it maintains the intermediate sear in a raised position and in engagement with the said member, the catch being then disengaged from the fly-wheel when the trigger is released, the effect of which 75 is to release the fly-wheel, which then enables the intermediary sear to sink and to disengage itself from the reciprocating member, while this latter hooks on to the ordinary sear which rose when the gunner 80 released the trigger, the next shot being fired by again pulling the trigger.

The locking shaft can occupy a position in which it prevents the catch from engaging the notch in the fly-wheel. In another 85 position it prevents any movement of the trigger and thereby gives the safety position. In a third position it no longer exerts any action upon the catch nor upon the trigger, and enables single shot fire to be 90 effected.

The invention is shown diagrammatically and by way of example in the accompanying drawings, in which the invention has been assumed to be applied to an automatic 95 gas-operated gun, in which the reciprocating member, the rate of movement of which is to be regulated, is a piston actuated by the expansive force of the powder gases in one direction (towards the rear) and by a 100 spring which stores up energy, in the other direction (forwardly).

In the accompanying drawings:
Fig. 1 is an elevation of the fire-regulat-

ing mechanism, the parts of which are shown in the position which they occupy for retarded automatic fire;

Fig. 2 is a corresponding plan view;
5 Fig. 3 is an elevation in which the right-hand wall of the casing has been removed and the intermediate sear is lowered;

Fig. 4 is a view similar to Fig. 3 in which the intermediate sear is raised so as to engage the piston;

10 Fig. 5 is a transverse section along V—V of Fig. 1;

Fig. 6 is a section similar to Fig. 3 in which the parts occupy a position corresponding to single shot firing;

15 Fig. 7 is an elevation of the fire-regulating mechanism showing the parts in the position which they occupy for rapid fire, that is to say, when the regulating mechanism 20 is not utilized;

Fig. 8 is a re-production of the former figure in which the right-hand wall of the casing is removed;

25 Fig. 9 is a detail showing the action of 25 the locking shaft upon the trigger when the two parts are in the safety position.

The present device comprises essentially a cylindrical member 1 having a circular groove 2; a recess 3 of a definite profile is 30 formed across this groove and in a direction parallel to that of the generatrices. This member 1, which is of sufficient mass to form a fly-wheel, has a circular recess 4, Fig. 5, which receives a spiral spring 5, one end of 35 which, 6, is fixed in a hole 7 formed at the base of said recess, the other extremity of which, 8, which is held by an abutment 9 carried by the corresponding faces of the member 1, abuts at 9^a against a projection 40 carried by the casing. Upon the opposite face of the fly-wheel 1 there is formed a tenon 10 which carries the fly-wheel with it in its rotary movement about a shaft 11 upon which there is also mounted a bearing 45 12, the hub 13 of which carries an eccentric lug 14 upon which is freely mounted a lever 15 having a projection 16, to which the piston P communicates a rearward movement when it moves backwards.

50 The position of this lever 15 depends, owing to the eccentricity of the lug 14, upon the position in which a spring-pin 17 holds the bearing 12. In order to hold this bearing 12 laterally two tongues 18 are formed 55 on the hub 13 which tongues, once in place, hold between them and the disc 19 of the bearing the corresponding wall of the casing 20, thus rendering any lateral displacement impossible.

60 For the purpose of assembling, there have been provided upon the casing, besides the circular recess 21 for the passage of the hub, two notches 22, Fig. 7, corresponding to the tongues 18. The movement of the lever 65 15 forwardly is limited by an abutment 23

fixed upon the casing in which latter two holes L. R. have been formed and in which the extremity of the pin 17 seats when the bearing 12 occupies either its extreme forward position or its extreme rear position; 70 these positions cannot be passed for the reason that one of the extremities 27—28 of a segment 29 provided upon the outer periphery of the disc 19 abuts in each of these positions against the locking shaft. 75

The trigger 30, of any usual form, has a nose 24, Fig. 9, and a cap 31 carrying a hollow shaft 32, upon which is pivoted the sear 33 which, besides its nose 34, has a notch 35 to the base of which is attached the extremity 36 of a spring 37 which forces forwardly the nose 38 of a catch 39, the cap 40 of which Fig. 2, carries a shaft 41 which passes through the sear 33 upon which the catch 39 is thus pivoted. This latter also has a tail-piece 25 of suitable shape. A spring 42, one of the extremities of which is attached to the sear 33 by the intermediary of a recess 43, while its other extremity is lodged in a recess formed in the rear portion of the casing 20, tends to hold the nose 34 constantly in its raised position.

The trigger 30 and the sear 33 can rotate as a whole about a shaft 45 fixed upon the casing and passing through the hollow shaft 32, the extremities of which project slightly through the cap 31 on each side and can fit into slides 46 (Figs. 1 and 2) formed upon each of the inner faces of the casing, this arrangement enabling assembling to be effected 100 before the shaft 45 is put in place.

The rotation of the trigger can only take place when one of the two flats 47, Fig. 9, formed upon the locking-shaft 48 comes into position opposite the nose 24 of the trigger 30 and allows it to pass; in the other positions of the shaft 48 the nose 24 abuts against it, and the trigger 30 and consequently the sear 33 are locked in their raised position. 110

The locking-shaft 48 carries furthermore, a lug 49 forming a cam and acting upon the tail-piece 25 of the catch 39 and is held laterally by an assembling lug 50, Fig. 7, a notch 51 having been provided in the casing 115 for the passage of the two lugs 49 and 50 when assembling.

A lever 52 having a stud 53 is fixed to the extremity of the shaft 48 and renders it possible to lock this latter in any one of the three positions which it can occupy. With this end in view the extremity 54 of the stud 53 can be lodged in one of the three recesses C, A, S formed on the outer face 120 of the casing.

Near the front of the device, an intermediate sear 54', which can oscillate about a shaft 55 fixed upon the casing, carries at one of its extremities 56, apart from its nose 57, a roller 58 which is held constantly upon 130

the outer periphery of the fly-wheel 1 by the action of a coil-spring 60 on its tail portion 59; the lower portion of this spring is lodged in a recess 61 of the casing while the 5 upper portion is received in a recess 62 of the tail portion 59.

The nose 57 will be in its engaging position when the roller 58 bears upon the circular periphery of the member 1; it will be 10 withdrawn when this same roller is opposite the recess 3, the profile of which has been designed in such a manner that it causes a positive raising of the roller.

The profile of the nose 57 of the intermediate sear 54' and the profile of the corresponding notch in the piston P are formed in such a manner that the nose 57 is always driven downwards by the piston during the forward movement of this latter.

20 The retarding mechanism as described apart from its safety device, enables fire to be effected either as single shot fire, firing at a retarded rate and finally, firing at the maximum rate.

25 In order to understand the action of the device, it will be preferable to examine each of these different functions of the fire-regulating mechanism in succession:

(1) *Retarding rate of fire.*—The pin 17 30 of the bearing 12 is placed at L and the stud of the lever 53 at A in such a manner that the locking shaft 48 allows the nose 24 of the trigger 30 to pass, without however, allowing the nose 38 of the catch 39 to engage 35 the fly-wheel 1. The trigger 30 is held in the firing position, thus preventing the nose 34 of the sear 33 from intervening in the method of operation of the weapon. In its rearward stroke which follows firing of the shot, 40 the piston P strikes, by means of a shoulder p, against the nose 16 of the lever 15 which it takes with it to the end of its stroke. By the intermediary of the tenon 10, this lever communicates a rotary movement to the fly-wheel, which continues after the stoppage 45 of the piston during a period of time which varies according to the impulse which caused it. When it ceases, a reverse movement takes place which brings back the fly-wheel 1 and the lever 15 to their original position under the action of the spring 5 which had been tensioned during the first movement.

At the beginning of the movement of the 55 fly-wheel, the roller 58 which was at the bottom of the recess 3 has risen and the nose 57 on the intermediate sear 54' has come into position and has locked the piston at the beginning of its forward stroke. Only when 60 the fly-wheel 1 returns to its original position, does the recess 3 again come opposite the roller 58, enabling this latter to move down under the action of the spring 60 and under the combined action of the profiles 65 of the nose 57 and the corresponding notch

of the piston; the nose 57 moves down and the piston can again make a forward stroke under the action of the recuperating spring.

It will be easily seen that the retardation in firing corresponds to the duration of 70 movement of the fly-wheel. It is therefore sufficient to impart to this latter an impulse more or less great in order to obtain a more or less rapid rate of fire. The bearing 12 is provided for this purpose and its position 75 determines that of the lever 15. The impulse which this latter receives and which it therefore will transmit to the fly-wheel will be the greater, the sooner it is acted upon by the piston. The slowest rate of fire is 80 obtained when the spring-pin 17 which fixes the bearing 12 is at L. As this pin is moved from L towards R a more and more rapid rate of fire is obtained, for the corresponding position of the lever subjects this latter 85 to the action of the piston through a path which becomes shorter and shorter.

2. *Maximum rate of fire.*—If the spring-pin 17 is moved to R (Fig. 8) the lever 15 is moved back so that the piston P cannot 90 reach it at the end of its stroke; the regulating mechanism therefore does not intervene any more in the functioning of the gun which fires at its maximum rate.

Single-shot firing.—If the lever 52 is 95 brought to C (position shown in Fig. 6) the lug 49 of the locking shaft 48, the flats 47 of which still allow the nose 24 of the trigger 30 to pass, has moved away completely and no longer acts upon the tail-piece 25 100 of the catch 39. This latter is pushed forward by the spring 37 and its nose 38 bears upon the outer periphery of the fly-wheel 1. The profile and position of this nose 38 are such that it moves away to allow the passage of the recess 3 during the forward movement of the fly-wheel, but on the contrary, during the return movement it strikes the edge of this recess and immobilizes the fly-wheel 1. In order to free this 110 latter the trigger 30 must be released and on resuming its position of rest it disengages the catch 39 from the recess 3, the nose 38 of the catch 39 moving away from the periphery of the fly-wheel 1, describing an arc 115 of a circle about the axis 45.

The method of operation is therefore the following:

When the trigger 30 is pulled, the nose 34 of the sear 33 moves away, as has been seen 120 above, and the shot is fired. As before, in its stroke towards the rear, the piston P engages the lever 15 which imparts a rotary motion to the fly-wheel 1. This latter will be immobilized by the action of the nose 38 125 of the catch 39 upon the edge of the recess 3, when it was about to return to its original position under the action of the spiral spring 5. The piston is then engaged by the nose 57 of the intermediate sear 54. If the trig- 130

ger 30 is then released the fly-wheel 1 is liberated, the intermediate sear 54' sinks and disengages itself from the piston P but at this time the nose 34 of the sear 33 engages in a corresponding notch in the piston. No further shot can be fired except by pulling the trigger 30, which disengages the nose 34 of the sear 33 from the notch in the piston. It follows that only one shot can be 10 fired for each action upon the trigger.

Safety device.—In order to prevent any functioning of the gun and consequently the firing of any shot, it is sufficient to bring the lever 52 into the position S, the result of 15 which is to place the locking shaft 48 in such a position that, by means of the nose 24 of the trigger 30 it immobilizes the trigger and sear in their raised position, the nose 34 of the sear 33 being thus held in its 20 engaging position.

It will be easily understood that each of the devices enabling these methods of firing to be obtained could be constructed separately.

25 The present invention therefore comprises three different apparatus:

1. Apparatus enabling a retarded rate of automatic fire to be obtained as well as the safety position.

30 2. Apparatus enabling a retarded rate of automatic fire to be obtained, single-shot fire and safety position.

3. Apparatus of the class described which renders it possible to obtain a retarded rate of automatic fire, single-shot fire, rapid fire and the safety position.

The form of each of these members and their arrangement relative to each other enables them to be quickly assembled and 40 disassembled without having to employ any tools. When disassembling it is sufficient to proceed as follows:

1. Move the lever 52 beyond its extreme position S so that the tenon 50 comes opposite the notch 51 and disengage the locking-shaft 48.

2. Exert sufficient pressure upon the sear 33 in a direction substantially parallel to that of the slides 46 to release the trigger 50 and sear as a whole, which can be withdrawn at the top.

3. Withdraw the shaft 55, which enables the intermediate sear 54' to be removed.

4. Withdraw the shaft 11 and remove the 55 fly-wheel 1 and the lever 15.

5. Remove the bearing 12 after having brought the tongues 18 into position opposite the notches 22.

In order to assemble the parts, each of 60 these operations should be effected in the reverse order, before placing the fly-wheel 1 in position it is necessary to compress the spring 5 to the extent of about one revolution and to engage it against the abutment 9.

I claim:

1. A firing regulator for automatic fire-arms, comprising in combination a casing, a fly-wheel mounted in said casing, a reciprocating member forming a part of the breech closing mechanism of the fire-arm and adapted to rotate said fly-wheel, a spring for returning said fly-wheel to its original position, and a lever movable independently of, but controlled by said fly-wheel and adapted to lock said reciprocating member. 75

2. A firing regulator for automatic fire-arms comprising in combination a casing, a fly-wheel mounted in said casing, a lever mounted adjacent said fly-wheel, a reciprocating member forming a part of the breech closing mechanism of the fire-arm and adapted to strike said lever to rotate said fly-wheel and a spring for returning said fly-wheel to its original position, and a lever movable independently of, but controlled by said fly-wheel and adapted to lock said reciprocating member. 85

3. A firing regulator for automatic fire-arms, comprising in combination a casing, a fly-wheel mounted in said casing, a lever adjustably mounted adjacent said fly-wheel, a reciprocating member forming a part of the mechanism of the fire-arms and adapted to strike said lever sooner or later, according to the angular position of this latter, to rotate said fly-wheel and a spring for returning said fly-wheel to its original position. 90

4. A firing regulator for automatic fire-arms, comprising in combination a casing, a fly-wheel mounted in said casing, a lever adjustably mounted adjacent said fly-wheel, a reciprocating member forming a part of the mechanism of the fire arm and adapted to strike said lever, a tenon on said fly-wheel adapted to be engaged by said lever to rotate said fly-wheel and a spring for returning said fly-wheel to its original position. 105

5. A firing regulator for automatic fire-arms, comprising in combination a casing, said fly-wheel having a recess, a reciprocating member adapted to rotate said fly-wheel, a pivoted lever, a roller on said lever engaging said recess, said lever having a nose adapted to lock said reciprocating member as long as said roller is moved out of said recess by the rotation of the fly-wheel. 115

6. A firing regulator for automatic fire-arms, comprising in combination a casing a trigger in said casing, a fly-wheel mounted in said casing, said fly-wheel having a recess, a reciprocating member adapted to rotate said fly-wheel and a catch actuated by the trigger for locking said fly-wheel. 125

7. A firing regulator for automatic fire-arms comprising in combination a casing, 130

a trigger in said casing, a fly-wheel mounted in said casing, a lever connected to said fly-wheel, a reciprocating member normally adapted to engage said lever to rotate said fly-wheel and means for moving said lever to a position where it does not contact with said reciprocating member.

8. A firing regulator for automatic firearms, comprising in combination a casing, a fly-wheel mounted in said casing, a bearing for said fly-wheel, said bearing having an eccentric hub, a lever mounted upon said hub, a reciprocating member adapted to engage said lever and means for adjusting the position of said lever relative to the reciprocating member by means of said hub.

9. A firing regulator for automatic firearms, comprising in combination a casing, a fly-wheel mounted in said casing, a bearing for said fly-wheel, said bearing having an eccentric hub, a lever mounted upon said hub, a reciprocating member adapted to engage said lever, means for rotating said hub to adjust said lever and means for locking said hub in different positions.

10. A firing regulator for automatic firearms comprising a casing, a trigger mounted in said casing, a sear actuated by said trigger, a fly-wheel adapted to be rotated by a reciprocating part of the mechanism of the fire-arm, a locking shaft in said casing, a recess in said fly-wheel adapted to be engaged by said sear, a lug on said locking shaft adapted to prevent said sear from engaging said recess and means for rotating said locking shaft.

11. A firing regulator for automatic firearms comprising a casing, a trigger mounted in said casing, a sear actuated by said trigger, a catch on said sear, a fly-wheel adapted to be rotated by a reciprocating part of the mechanism of the fire-arms, a locking shaft in said casing, a recess in said fly-wheel adapted to be engaged by said catch, a lug on said locking shaft adapted to prevent said catch from engaging said recess and means for rotating said locking shaft.

12. A firing regulator for automatic firearms comprising in combination a casing, a trigger mounted in said casing, a sear actuated by said trigger, a catch on said sear, a fly-wheel adapted to be rotated by

a reciprocating part of the mechanism of the fire-arm, a recess in said fly-wheel adapted to be engaged by said catch, a locking shaft in said casing, a projecting part and a lug on said shaft, means for rotating said locking shaft into three positions, whereby in one position, to cause said projecting part to prevent any movement of the trigger, in another position to cause said lug to prevent said catch from engaging said recess, and in a third position to clear said projecting part and said lug.

13. A firing regulator for automatic firearms comprising in combination a casing, a trigger mounted in said casing, a sear actuated by said trigger, a fly-wheel mounted in said casing and adapted to be rotated by a reciprocating part of the mechanism of the gun, said fly-wheel having a recess, an intermediate sear, a roller on said intermediate sear adapted to engage said recess, said intermediate sear having a nose adapted to engage the reciprocating part of the mechanism of the fire-arm when forced out of the recess by the rotation of the fly-wheel, a catch on said trigger actuated sear adapted to engage said recess and a shaft which is rotatable to cause said catch to engage or not in said recess.

14. A firing regulator for automatic firearms comprising in combination a casing, a fly-wheel mounted in said casing, said fly-wheel being mounted in a bearing having an eccentric hub, a lever mounted upon said hub and adapted to be actuated by a reciprocating portion of the mechanism of the gun, a tenon on said fly-wheel adapted to be engaged by said lever, means for rotating said hub to adjust the position of said lever, a trigger mounted in said casing, a sear actuated by said trigger, said sear having a catch adapted to engage a recess in said fly-wheel, an intermediate sear, a roller carried by said sear and resiliently pressed into said recess, a nose on said sear adapted to engage the reciprocating portion of the gun when the roller is forced out of the recess, and a shaft having a lug adapted to move the catch of the trigger actuated sear out of engaging position with said recess.

CHARLES SUTTER.
